METHOD AND MEANS FOR PROTECTING
FLUORESCENT COATINGS AND THE
LIKE

Gerald S. Quinn, Salem, Mass., assignor to Sylvania Electric Products Inc., Salem, Mass., a corporation of Massachusetts

Application January 3, 1946, Serial No. 638,747

6 Claims. (Cl. 316—17)

1

This invention relates to means and method for protecting fluorescent or other types of coatings for lamps or other electronic devices prior to the final exhausting, gassing and sealing off operations.

In the manufacture of electronic devices having such coatings it is highly desirable to exhaust and seal the envelope thereof before an extended elapse of time subsequent to the application and processing of the coating. If the finished coating is subjected to prolonged exposure to an oxidizing or impure atmosphere its efficiency is impaired.

It is an object of the present invention to protect the coating from deterioration when it becomes necessary or desirable to delay the final exhaustion and sealing of the device.

A further object of the invention is to provide means to protect the device from excessive internal pressure when it is subjected to heat.

Other objects and features of the invention will more fully appear from the following description taken in connection with the accompanying drawings and will be particularly pointed out in the claims.

The invention applies particularly to electronic devices having a fluorescent or other coating and which require that time consuming operations be performed thereon after the coating has been applied and before its envelope is finally sealed off.

To protect the coating from deterioration during this intervening period an inert gas is introduced into the envelope and the air therein flushed out, pumped out, or otherwise removed. The envelope is then temporarily sealed off.

The invention further provides that a relatively high heat may be applied to the lamp after being temporarily sealed off without causing rupture of the envelope due to excessive pressure developed by the heated gas within. Pressure relief means are provided in the form of a seal at the end of the envelope exhaust tube. The seal is composed of glass of low softening point. The softening point of the glass seal being of such a value that it will soften before the glass of the envelope and in so doing will permit harmful pressure developed in the envelope to be vented through the exhaust tube. Moreover, the glass seal also acts as a check valve to prevent a reverse

flow of air into the envelope since when the pressure within becomes reduced to a safe degree the natural flow of the glass while still hot automatically reseals the envelope. The fluorescent coating is thereby completely protected from contaminating atmosphere throughout the manufacture of the lamp or other device.

To provide a better understanding of the invention a specific embodiment thereof will now be described and illustrated in the drawings in which:

Fig. 1 is a general view of a fluorescent lamp tube of circular form after its inner wall has been coated with a fluorescent coating.

Fig. 2 illustrates the lamp tube together with means for introducing a protective gaseous atmosphere into the envelope.

Fig. 3 is an enlarged detail sectional view of the base portions of the lamp illustrating the manner in which the lamp is temporarily sealed off.

Fig. 4 illustrates somewhat diagrammatically an oven containing a lamp upon which a straightening operation is being performed.

Figs. 5 and 6 illustrate the manner in which a specially constructed pressure relief sealing tip functions to protect the lamp and its coating.

It will be understood that the invention may be applied to any device having a sealed glass envelope with at least a portion of its inner wall coated with fluorescent material or having a coated element therein susceptible to contamination.

The lamp illustrated when completed is of circular form and its tubular envelope lies substantially in a plane.

To facilitate its manufacture, however, the lamp tube is first given a circular outline and a slightly spiral convolution thus disposing its ends 2 in offset relation to permit fabricating operations such as the fusing of stem members upon the lamp tube.

Fig. 1 of the drawings illustrates a lamp tube partially in section to show its fluorescent coating 3. The coating is applied and baked to remove all solvents and binder material in the conventional manner and upon completion of the coating the ends of the tube are closed by fusing thereto the stem members 4. The stem members are provided respectively with exhaust tubes 5 and 6.

In the conventional manner of manufacturing tubular lamps the final steps in their manufacture are carried out in fairly rapid succession after the fluorescent coating is applied and treated. In the present invention, however, the coating is protected from contamination by contact with impure or oxidizing atmospheres during an intervening period of time after the coating is applied and before final sealing off of the lamp.

A desirable means for protecting the coating is to introduce an inert gas to replace the air within the tube. To accomplish this end the gas is introduced through one of the exhaust tubes for example, the tube 6 from a tank of gas 7 which is connected to the tube 6 by means of a pipe 8. The flow of gas is controlled by a valve 9 in the pipe 8. A sufficient quantity of gas is admitted to flush out substantially all of the air in the lamp. The air passes out through the exhaust tube 5. When the desired condition within the lamp has been obtained both exhaust tubes are sealed off thus protecting the coating indefinitely.

The inert atmosphere may be introduced in any desired manner for example, a single exhaust tube may be used in which case the air in the envelope is removed by a pump and inert gas introduced thereafter through the same tube.

A further feature of the invention is to protect the lamp from excessive internal gas pressure when it is subjected to the application of heat. In the production of the type of lamp described herein the spiral configuration of the tube must be flattened to provide a practical lamp and such operation must be executed after the application of the fluorescent coating.

This operation requires that the lamp be heated sufficiently to permit the tube to be bent until it lies substantially in a flat plane. It will also be noted that the straightening operation is performed after the protective inert gas has been sealed into the lamp.

To execute the straightening operation the lamp is desirably placed in an oven 10 wherein its temperature is raised to the point where the glass becomes slightly plastic. A weight 11 is placed upon the high end of the tube and its other end is preferably lightly clamped as shown in Fig. 4. The action of the weight gradually bends the tube until it lies in a flat plane upon the support 12 within the oven.

During the straightening operation the gas sealed within the lamp is heated and greatly increases the pressure therein which tends to expand and distort the lamp. To prevent this possibility a relief and check valve device is provided to relieve excessive pressure within the lamp. The desired result is achieved by constructing the outer portion 13 of one of the exhaust tubes for example, the tube 5 of soft glass or similar material having a melting point lower than that of the material of the lamp itself. Desirably a short section 13 of soft glass tubing or a bead is used to seal off the tube 5.

The high temperature of the oven causes the soft glass to become more plastic than the lamp itself. Consequently the increased pressure within the lamp forces an opening in the exhaust tube 5 as shown in Fig. 5 thus relieving the excessive pressure.

When the pressure becomes normalized the plasticity of the soft glass acts to close the opening blown therein thus again sealing off the lamp and automatically protecting the fluorescent coating.

The relief and check valve device may be situ-

ated in the exhaust tube as described or it may be situated at any desired point in the envelope.

After the lamp has become flattened under the action of the weight 11 it is allowed to cool and is then removed from the oven and may be completed at any time.

To complete the lamp the seal 13 is broken after which the tube 5 is connected to a pump to exhaust the lamp which then may be finally sealed and completed by basing and performing whatever other operations may be required to place the lamp in operating condition.

What I claim is:

1. A method of temporarily protecting from contamination an element within the envelope of a thermionic device comprising, introducing a protective gaseous atmosphere into the envelope, forming a seal to keep the gas therein, subsequently performing added operations upon the device including heating the device to a temperature sufficient to break said seal, and cooling the device sufficiently to effect a re-sealing of the broken seal.

2. A method of temporarily protecting from contamination an element within an envelope of a thermionic device comprising introducing a protective gaseous atmosphere into the envelope, forming a seal to keep the gas therein, applying heat to the envelope while sealed, said heat effecting automatic venting of excessive pressure within the lamp caused by its rise in temperature through said seal and cooling the envelope to cause said seal to reseal the envelope after the pressure therein is reduced.

3. A method of temporarily protecting an internal fluorescent coating for a thermionic device during its manufacture comprising applying a coating of fluorescent material to the inner wall of its envelope, introducing an inert gaseous atmosphere into said envelope, forming a seal to keep the gas therein, performing additional operations thereon while thus sealed including heating the device to a temperature sufficient to break said seal, and cooling the device sufficiently to effect a re-sealing of the broken seal.

4. A method of temporarily protecting an internal fluorescent coating for a tubular thermionic device during its manufacture comprising applying a fluorescent coating to at least a portion of its inner wall, closing the ends of the tubular envelope to present an opening substantially smaller than the tube; introducing an inert gas at one end of said tube thereby flushing the air in the envelope out through the aperture at its other end, forming a seal at both ends of the tube thereby enclosing the gas therein, performing additional operations thereafter upon the device while thus sealed including heating the device to a temperature sufficient to break said seal, and cooling the device sufficiently to effect a re-sealing of the broken seal.

5. A method of temporarily protecting a fluorescent coating upon the inner wall of the tubular envelope of a fluorescent lamp during its manufacture comprising applying the fluorescent coating to the open ended envelope, finishing the coating, fusing stem assemblies having an exhaust tube in at least one thereof to the respective ends of the tubular envelope, introducing an inert atmosphere into said envelope through said exhaust tube, forming a seal on the outside end of said exhaust tube, subsequently performing additional operations upon the lamp while thus sealed including heating the lamp to a temperature sufficient to break said seal, and cooling the lamp

sufficiently to effect a re-sealing of the broken seal.

6. A method of temporarily protecting the fluorescent coating upon the inner wall of a tubular fluorescent lamp during its manufacture comprising applying said coating to the open ended lamp envelope, fusing stem assemblies to the ends of said envelope, introducing into said envelope an inert atmosphere, forming a seal to keep the inert atmosphere therein, applying heat to said envelope while sealed to permit of envelope forming operations, including heating to a temperature sufficient to break said seal, and cooling to a temperature sufficient to effect a re-sealing of the broken seal.
